UNITED STATES PATENT OFFICE

2,489,819

LOAD RELEASING MEANS

John C. Rumsey, Mission, Kans.

Application July 3, 1946, Serial No. 681,395

3 Claims. (Cl. 294—83)

1

The present invention relates to automatic load-release devices and aims to provide a novel and improved construction of appliance adapted to satisfy all the requirements of an efficient and practical device of this type as regards its load-supporting function, and also provide reliable releasing means adapted to operate to effect release of the load upon slackening of the pull of such load to a predetermined point or fraction of the full actual weight of the load.

The invention relates particularly to devices of this class which are used in aerial transportation and require load-releasing means operative to maintain a continuous and reliable holding and supporting connection with the load, and including means also operating to insure instant release of said supporting connection at the landing point, or place of delivery of the load.

For the embodiment of my invention, I provide a device comprising separable connecting elements designed for attachment to the transport or carrier (such as a parachute) and to the load respectively, and also latching means operative to maintain said elements connected in securely latched relation both prior to and after application of the load, after which the load-releasing function operates automatically in response to a slackening of the pull exerted by the load to a given predetermined point or given weight factor representing only a part of the actual or full weight of the load.

For accomplishing these objects of my invention I have devised a construction comprising separable elements designed to be attached to the parachute or transporting member and to the load respectively, and operative to yieldingly support the load until only a given minimum fraction of the weight of the load is transmitted to the supporting member, when said separable elements of the appliance are automatically disengaged, thereby freeing the transporting member or carrier entirely from the load at the point of release.

It is also sought to provide a neat and very compact construction, composed of but few operating parts, most of which are practically entirely enclosed and protected in a housing structure comprising the main structural element of the improved appliance.

With the foregoing general objects in view, the invention will now be described by reference to the accompanying drawing illustrating one practical form of construction which I have devised and found to be suitable for the efficient embodiment of the proposed improvements, after

2

which those features and combinations deemed to be novel and patentable will be particularly set forth and claimed.

In the drawing—

Figure 1 is an elevation illustrating a load-releasing device constructed in accordance with the present invention, and the parts thereof shown in their operative relation prior to the load-releasing operation;

Figure 2 is a longitudinal sectional view of the device, representing a section taken on the line 2—2 of Figure 1, and with dotted lines indicating the load-supporting connections in their released and detached relation; and

Figure 3 is a transverse sectional detail view representing a section taken on the line 3—3 of Figure 2.

Referring now to the accompanying drawing in detail, the improved appliance is illustrated as comprising a tubular form of casing 10 constituting the main body member of the device, one end of which is closed and provided with a swivel link 12 for attachment to the cable or other supporting means such as the harness suspended from a parachute or other transporting carrier (not shown). The casing 10 serves as a housing for enclosing a pair of coil spring elements, including a compression spring 14 which is seated in and permanently secured (as indicated at 16) within the lower end of said casing (see Figure 2), and also a strong tension spring 18, the upper end of which is provided with a T form of attachment 20 designed for detachable engagement with a pair of notches or recesses 22 formed at the upper end of a longitudinal slot 24 provided along one side of said casing 10. This slot 24 permits the insertion of said spring 18 into the interior of the casing for removable latching and releasing purposes, and the lower end of said spring 18 is provided with a pivotal connection with a loop 26 forming part of a second swivel link 28 designed to serve as a means of connection to the load which is to be releasably carried by the appliance.

The compression spring 14 is designed to serve as a yielding cushion for certain of the parts after these have been assembled in the operative and latched relationship illustrated in Figures 1 and 2, with the spring 18 enclosed within the casing 10.

In this relation the spring 18 is maintained under a given tension by having its upper end anchored by means of the attachment 22 and its lower end drawn down by the link 28 and the latter then latched after having applied a certain degree of pressure to the other spring 14.

The lower portion of the casing 10 is formed with a pair of diagonal slots 39 on opposite sides of the longitudinal slot 24, for accommodating the movement of the upper crossbar 28' of the link 28 when assembling the parts in the relation just described.

The latching means for retaining the parts in the aforesaid relation consists of a semicylindrical element 32 pivoted at 34 to the sides of the casing 10 and formed with notches 36 in its lower edge for latching engagement with the crossbar 28' of said link 28. A leaf spring 38 is attached by a rivet 40 to said latch element 32 and tends to actuate the latter normally outward into unlatched position, as indicated by the dotted lines in Figure 2. A loop or keeper member 42 on the casing 10 serves to limit said outward movement of the latch element 32.

A leaf spring 45 is also anchored at 46 within the top portion of the casing 10, with the lower end of said spring extending in position for engagement with the attachment 20 supporting the spring 18, and exerting thereon a pressure sufficient to dislodge said attachment from the notches 22 when the pull on the spring 18 falls below a given tension.

In operation, the load is supported by the parts occupying the positions illustrated by the full lines in Figures 1 and 2. In this relation the weight of the load is divided between the springs 14 and 18—the latter being pulled down under tension and the spring 14 supporting the balance of the load under compression.

The parts are assembled initially and maintained in the said relation by the latching means above described, with the springs 14 and 18 maintained under certain degrees of compression and tension respectively, and this latching means is sufficiently secure to allow all the necessary handling of the appliance, preparatory to operation under load, as when dropped for a parachute landing. When this takes place, and the load is therefore taken up by a pull on the connecting link 28, the spring 14 is still further compressed, with the result that the latch 32 is released and therefore becomes automatically disengaged from the load-supporting link 28. Thereafter during the continued flight the load is supported by the joint action of the two springs 14 and 18 and hence any variation in the pull of the load will be automatically accommodated by corresponding or compensating spring action, within a given limit as represented by a predetermined minimum pull of the load. Such predetermined limit corresponds to a retraction of the spring 18 sufficient to bring the crossbar 28' to the upper end of the slots 39, when the pressure tending to hold the attachment 20 in position will be overcome by the action of the spring 45, which accordingly acts to eject or dislodge said attachment from the notches or recesses 22, thus leaving the parts carrying the load entirely unsupported and free—as represented by the dotted line positions, in Figure 2 of the drawing.

It will therefore be seen that I have devised a practical and efficient arrangement and construction for the carrying out of all the principal objects of my invention, including the provision of a de-

sign in which the important operating elements of the construction are all securely housed and protected by being enclosed within the remainder of the appliance. While I have illustrated and described what I now regard as the preferred form of construction for the embodiment of my improvements, I desire to be understood as reserving the right to make whatever changes or modifications may be deemed to fall within the spirit and scope of the appended claims.

Having described my invention, what I claim and desire to secure by Letters Patent is:

1. Load releasing means for releasing loads from parachute carriers and the like, comprising a main body member for attachment to the carrier, a link or connector for attachment to the load and provided with a tension coil supporting spring detachably connected with said body member, a compression spring engaged by said link and cooperating with said coil spring for supporting the load, and means operating automatically as the tension on said coil spring imposed by the load falls to a given minimum limit for effecting detachment thereof from said body member.

2. Load releasing means for releasing loads from parachute carriers or the like, comprising a main connector member for attachment to the carrier, a connecting link for attachment to the load and provided with a tension coil supporting spring detachably connected with said main connector member, a compression spring engaged by said link and cooperating with said coil spring for supporting the load, an automatic latching element for engaging said link and retaining the parts in predetermined latched relation while releasing the link under normal load pressure upon said compression spring, and means operating automatically as the tension on said coil spring imposed by the load falls to a given minimum limit, for effecting detachment thereof from said main connector member.

3. Load releasing means for releasing loads from parachute carriers or the like, comprising a tubular body or main connector member for attachment to the carrier, a connecting link for attachment to the load and provided with a coil supporting spring enclosed by said body member and detachably connected with said main connector member, a compression spring also enclosed by said tubular body and cooperating with said coil spring for supporting the load, and means operating automatically as the tension on said coil spring imposed by the load falls to a given minimum limit for effecting detachment thereof from said body or main connector member.
